BUILDING STRUCTURE

Edward A. Haupt, Pittsburgh, Pa.

Application August 24, 1931. Serial No. 553,867

5 Claims. (Cl. 72—18)

My invention relates to building structures and particularly to building blocks for wall structures which emulate a plurality of standard bricks.

5 One object of my invention is to provide a relatively large brick or block preferably made of the usual brick clay and processed in the usual manner, that emulates a plurality of standard bricks for facilitating the building of the wall 10 by obviating the handling and laying of a relatively large number of individual bricks.

Another object of my invention is to provide a building block having the above noted characteristics wherein the blocks are interchangeable 15 and may be laid in cooperating relation to form either a straight wall or a right-angle corner wall.

A further object of my invention is to provide a building block wherein the end brick of alternate tiers are disposed in spaced superimposed relation 20 and are provided with spacing material so disposed that the application of mortar between the adjacent blocks cannot interfere with the accurate spacing of the adjacent cooperating blocks.

25 A further object of my invention is to provide a building block of the above noted character wherein spacing material is provided on the upper surfaces of the upper tier of bricks for supporting the super imposed blocks in spaced 30 relation thereupon and wherein notches are provided in the said surface between the spacing material for receiving tiers for fastening the blocks to a wall structure.

These and other objects that will be made apparent throughout the further description of my invention are attained by means of the building block or brick hereinafter described and illustrated in the accompanying drawing, wherein

40 Figure 1 is a perspective view of an improved building block embodying features of my invention.

Fig. 2 is a top plan view of the block illustrated in Fig. 1, shown in assembled relation to a wall structure.

45 Fig. 3 is a transverse section through a building block taken on the line III—III of Fig. 2, and

Fig. 4 is a perspective view of two improved building blocks assembled to form a right-angle wall section.

50 Referring to the drawing, my improved building block or brick comprises a block of material 5, the thickness of which is equal to the width of a standard baked clay brick and which is provided with longitudinal grooves 6 and staggered transverse grooves 7 which serve to define four tiers

of standard bricks arranged in the usual staggered, over-lapped relation, the grooves being of sufficient depth to receive and securely retain mortar 8 for the purpose of giving the block the appearance of a plurality of brick laid with the 60 usual mortar binder.

The end bricks 9—11 and 12—13 project beyond the end bricks 14—15 and 16—17 respectively of alternate tiers of bricks and are superimposed in aligned spaced relation to provide 65 spaces 18—19 and 21—22 for receiving respectively the bricks 12—13 and 9—11 of adjacent blocks.

By reason of the arrangement of the projecting end bricks in superimposed aligned relation, the 70 end bricks of similar blocks may be interlaced to constitute either a straight wall section or a right-angle corner section as shown in Fig. 4, without requiring special bricks for corner structures.

75 In order to facilitate assembly of the blocks, the end bricks are provided with integral spacing material or angles 23 disposed on the under-side of the projecting bricks and on the ends of the adjacent brick of the adjacent tier, the spacing material thus constituting an angular projection disposed in the upper inner corner of the spaces 18, 19 and 21. This location is the most desirable for the following reasons:

80 In assembling two adjacent blocks, whether for a straight wall section or a corner section, mortar is placed on the upper surface of bricks 11 and 21 and 22, and the adjacent block is moved into position by a sliding motion. The mortar presses the bricks 12 and 13 upwardly against 85 the upper portion of the spacing angle 23, thus giving the brick proper elevation. The portion of the spacing angle 23 on the end bricks 14, 15 and 17 properly position the adjacent bricks in a lateral direction.

95 Placing the spacing angle 23 at the lower inner corner of the space between the projecting brick would give difficulty because the mortar would be crowded upon the surfaces of the spacing angle and thus would prevent the proper assembly of the adjacent brick because of the interposed mortar. For this reason the spacing angles are located as shown in Figs. 1 and 2.

To maintain the proper space between a block 100 and the block superimposed thereon, I provide integral spacers 24 on the upper surfaces of each upper tier of bricks adjacent the vertical grooves. Mortar is placed between the spacers 24 on the block and the spacers support the superimposed 105 block. If the spacers 24 were disposed on the 110

under surface of the blocks, mortar on the upper surface would interfere with the proper positioning of the superimposed block.

5 The upper surfaces of the block are provided with notches 25 for receiving the bent ends of the wall-ties 26 which are secured to the sheathing 27 of the wall structure 28 and which serve to fasten the blocks to the wall structure. The notches 25 are disposed between the spacers 24 and consequently the wall-tiers lie in the spaces 10 between the spacers 26 and are embedded in the mortar before a block is placed in position.

15 After the blocks are assembled, the grooves 6 and 7 are partially filled with mortar to emulate a wall made of individual brick, and the wall has the appearance of the usual brick wall.

20 By reason of my improved building brick, the number of units constituting the wall structure, the cost of laying a wall and the time required are materially reduced. The cost of manufacture of my improved brick block is less than that of the number of brick emulated in the block structure because of the reduction of the 25 number of separate units that must be handled in the manufacturing process to produce an equivalent wall area.

25 While I have shown a block made to emulate four tiers of brick having three bricks in each tier, or twelve bricks in all, it is obvious that the 30 number of tiers or the number of bricks in each tier may be varied without departing from the spirit of my invention, and that a block having but two tiers of brick emulated thereon may readily be assembled to constitute either a straight wall section or a right-angle wall section.

35 I claim as my invention:

1. The combination with a building block of material formed to emulate a plurality of standard building bricks that are defined by longitudinal and staggered transverse grooves in the front 40 faces of the block for receiving mortar, the defined bricks being arranged in at least two tiers with the bricks of each tier disposed in staggered relation to those of the adjacent tier, the defined 45 end bricks of one tier projecting beyond the end brick of the adjacent tier to provide spaces for receiving the projecting end bricks of a similar adjacent block, of a second block identical to the first block adapted to cooperate when the second 50 block is aligned therewith in the same plane and the projecting bricks of the second block are fitted within said spaces of the first block to form a straight wall section, or when the second block is disposed normal to the first block and when the projecting bricks of the second block 55 are fitted within said spaces of the first block to form substantially a right angle corner section, the under face only of the projecting brick and the end face of the adjacent brick being provided with spacing material substantially the thickness of the said grooves, for maintaining a predetermined spaced relation between bricks of adjacent blocks for providing mortar receiving spaces therebetween.

60 2. The combination with a building block of material formed to emulate a plurality of standard building bricks that are defined by longitudinal and staggered transverse grooves in the front 65 faces of the block for receiving mortar, the defined bricks being arranged in at least two tiers with the bricks of each tier disposed in staggered relation to those of the adjacent tier, the defined end bricks of one tier projecting beyond the end brick of the adjacent tier to provide 70 spaces for receiving the projecting end bricks of 75

a similar adjacent block, of a second block identical to the first block adapted to cooperate when the second block is aligned therewith in the same plane and the projecting bricks of the second block are fitted within said spaces of the first block to form a straight wall section, or when the second block is disposed normal to the first block and when the projecting bricks of the second block are fitted within said spaces of the first block to form substantially a right angle corner section, the upper face of the upper tier of bricks being provided with spacing material adjacent the transverse grooves and of substantially the thickness of a longitudinal groove for supporting a similar superimposed block in spaced relation thereupon to provide a mortar receiving space therebetween.

80 3. The combination with a building block of material formed to emulate a plurality of standard building bricks that are defined by longitudinal and staggered transverse grooves in the front face of the block for receiving mortar, the defined bricks being arranged in four tiers with the bricks of each tier disposed in staggered relation with respect to those of the adjacent tier, the defined end bricks of two alternate tiers projecting beyond the end bricks of the remaining tiers in superimposed spaced relation to provide spaces for receiving the projecting end bricks of an adjacent block, of a second block identical to the first block adapted to cooperate when the second block is aligned therewith in the same plane and the projecting bricks of the second block are fitted within said spaces of the first block, to form a straight wall section, or when the second 100 block is disposed normal to the first block and when the projecting bricks of the second block are fitted within said spaces of the first block to form substantially a right angle corner section.

105 4. The combination with a building block of material formed to emulate a plurality of standard building bricks that are defined by longitudinal and staggered transverse grooves in the front faces of the block for receiving mortar, the defined bricks being arranged in at least two tiers with the bricks of each tier disposed in staggered relation to those of the adjacent tier, the defined end bricks of one tier projecting beyond the end brick of the adjacent tier to provide 110 spaces for receiving the projecting end bricks of a similar adjacent block, of a second block identical to the first block adapted to cooperate when the second block is aligned therewith in the same plane and the projecting bricks of the second block are fitted within said spaces of the first block to form a straight wall section, or when the second block is disposed normal to the first block and when the projecting bricks of the second block are fitted within said spaces of the first block to form substantially a right angle corner section.

115 5. The combination with a building block of material formed to emulate a plurality of standard building bricks that are defined by longitudinal and staggered transverse grooves in the front faces of the block for receiving mortar, the de- 120
